(57) **CLAIM**

The ornamental design for a slide operation type dovetail groove sliding stage for precision equipment, as shown and described.

DESCRIPTION

FIG. 1 is a plan view of a slide operation type dovetail groove sliding stage for precision equipment showing my new design;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a reference perspective view thereof.

The broken lines in the drawings depict unclaimed environmental subject matter.
